SEDIMENT EDUCTORS FOR SETTLING CHAMBERS

Robert T. Steindorf, Milwaukee, Wis., assignor to Chain Belt Company, Milwaukee, Wis., a corporation of Wisconsin

Filed June 12, 1956, Ser. No. 590,939

3 Claims. (Cl. 15—1.7)

This invention relates to sediment eductors for settling chambers such as are widely employed in sewage disposal, liquid purification and analogous work, and it has for its principal object the provision of an improved eduction device which is less expensive to construct and more efficient in accomplishing the removal of settled matter from the floors of said chambers than have been the eductors heretofore proposed.

Although by no means specifically limited thereto, the present eductor may be advantageously employed with sedimentation apparatus such as that disclosed in prior U.S. Patents No. 1,947,429 to Townsend and Brower, and No. 2,150,865 to Shafer and Seidenstricker, and therefore for purposes of disclosure the invention has been illustrated in the accompanying drawings in connection with apparatus of this character. In such apparatus the removal of matter which has settled on the floor of the sedimentation chamber is effected by means of one or more horizontally extending pipes or tubes disposed a foot or more above said floor and moved slowly thereover, such pipes being provided with a series of longitudinally spaced depending nozzles into which the sediment is continuously forced by the hydrostatic pressure of the liquid in the chamber, for transfer through said pipes to a discharge duct connected therewith. In some instances the removal is effected or assisted by the application of suction to the tubes or discharge duct.

The instant invention utilizes in part the principles disclosed and claimed in an application filed concurrently herewith by my co-workers Arthur C. Lind and William J. Katz, Serial No. 590,940 filed concurrently herewith and entitled Method and Apparatus for Removing Sediment.

In the above mentioned drawings:

Figure 1 is a central vertical sectional view, partly in elevation, of a typical settling tank and sediment removal apparatus such as is disclosed in the above identified patents, with the said removal apparatus however, equipped with one form of sediment eductor constructed in accordance with this invention;

Fig. 2 is an enlarged plan view, partly broken away and in section, of the eductor and immediately associated parts shown in Fig. 1;

Fig. 3 is a front elevational view of the parts illustrated in Fig. 2;

Figs. 4, 5, 6 and 7 are enlarged cross sectional views of the eductor, taken respectively on the planes indicated by the lines 4—4, 5—5, 6—6 and 7—7 in Fig. 3, looking in the direction of the arrows;

Fig. 8 is a perspective view illustrating a preferred, although not the only, mode of constructing the eductor;

Fig. 9 is a plan view of a slightly modified example of the invention;

Fig. 10 is a front elevational view of the eductor shown in Fig. 9;

Fig. 11 is a cross sectional view on the plane indicated by the line 11—11 in Fig. 10, looking in the direction of the arrows; and

2

Figs. 12 and 13 are views illustrating modified cross sectional shapes the eductor may take.

Referring more particularly to Fig. 1, 15 indicates a sedimentation tank into which the liquid to be clarified is introduced through an influent conduit 16 and central feed well 17. The clarified liquid is discharged over a weir 18 to an effluent launder 19 provided at the top of the perimetric wall 20 of the tank and communicating with a discharge duct, not shown. The tank floor 21 slopes slightly from said wall to the center of the tank to facilitate drainage of the tank, and a sediment discharge conduit 22 extends through said floor radially from such center. An eduction manifold 23, surmounting and communicating with the inner end of said conduit 22, is appropriately journaled on the tank floor for rotation about a vertical axis and has one or more horizontally extending sediment eduction tubes 24 connected to its branches 25, one being shown. A tubular shaft 26 is secured to and extends upwardly from the manifold 23 whereby it may be rotated by means of a suitable source of power and speed reduction mechanism 27 to slowly traverse the eduction tube 24 over the tank floor 21. When only one eductor tube is employed, a counterweight 28 preferably is secured to the opposite manifold branch 25 to balance the apparatus.

Whereas in the constructions shown in the two prior patents mentioned the sediment eduction pipes were of circular cross section and were disposed a substantial distance above the chamber floor, with collecting nozzles depending from them to adjacent said floor, the eductor tubes of the present invention are essentially of non-circular cross section and extend over the tank floor in adjacent substantially parallel relation to the surface thereof. Thus, as will be readily understood from Figs. 2—11, the tubes there shown are of a rectangular cross section which provides four planar walls 30, 31, 32 and 33, and said tubes are canted about their longitudinal axis so that when viewed in cross section, as in Figs. 4—7, each of the said walls is inclined to the horizontal. With the direction of movement of the tube being as indicated by the arrows in these figures, the walls 30 and 31 may be respectively denominated the upper and lower forward walls, and the walls 32 and 33 respectively the upper and lower rearward walls.

As stated above, and clearly shown in Fig. 3, the eductor tube 24 is disposed adjacent the surface of the tank floor 21, thus dispensing with the necessity for the depending intake nozzles of the prior constructions, and in lieu thereof the lower forward wall 31 of the tube is provided with one or more sediment admission ports 34. As here shown, a series of such ports is provided adjacent the lower edge of said wall, and in accordance with the teaching of the Townsend et al. Patent No. 1,947,429 they progressively increase in size from the inward end of the tube to the outward end thereof, this for the reason that the respective zones from which the ports receive sediment increase in area in proportion to their distance from the axis of rotation.

As the tube is moved through the liquid and sediment at the bottom of the tank, the downwardly inclining wall 31 with its forwardly facing ports 34 greatly facilitates the entry of the sludge into the tube. However, it has also been found that the efficiency of an eductor constructed as above described may be further appreciably enhanced if a lip or flange 35 be provided below the ports 34, such flange being reversely inclined with respect to the wall 31 and extending forwardly and downwardly to proximity with the tank floor. The convergent surfaces of said wall and flange tend to fluidize the sludge blanket as the eductor moves through it, whereby the sediment passes to and through the ports 34 even more readily, with the result that substantially complete re-

moval is effected and the floor area immediately behind the moving eductor is practically free of sediment.

Since the volume of sediment in the tube of course increases from the outward end to the inward end thereof with the addition of each increment entering through the successive ports 34, the cross sectional area of the eductor should increase in like direction if a uniform velocity of sediment flow is to be maintained throughout the tube, which is desirable. The present eductor may be readily constructed to provide substantially uniform variation of its cross sectional area from end to end, with resultant optimum functioning.

Fig. 8 illustrates a preferred, although not the only, mode of constructing a rectangular eductor tube such as above described. That is to say, a rolled or pressed channel member of appropriate length is provided, the web 32' of which is of uniform width from end to end. The legs 30' and 33' of said channel however, are of substantially uniform tapering depth from end to end, as shown, with the leg 33' being of greater depth than the leg 30'. A strip 31' of uniform width throughout, and having the ports 34 drilled or punched in it, is positioned between and welded to the legs 30' and 33' of the channel, such strip being disposed in transverse parallelism with the web 32' of the channel and with its forward edge substantially flush with the tapering edge of the channel leg 30', and its rearward edge spaced from the tapering edge of the wider channel leg 33', thereby providing the longitudinal flange 35 extending the full length of the tube. A transverse filler piece 36 is provided at the narrow end of the channel whereby to close the outward end of the eductor.

Referring again to Figs. 2 and 3, at its larger end the eductor tube has attached to it a short converter section 37 which changes the cross section from rectangular to circular, and said section 37 in turn is secured to one end of an S-shaped pipe 38 the other end of which is attached to the branch 25 of the manifold 23. A spiral scraper blade 39, surrounding the base of said manifold and rotatable therewith, insures that matter settling in the central portion of the tank adjacent the manifold will be moved outwardly into the path of the inward end of the eductor for removal thereby.

The inverted V-shaped surfaces provided by the forward and rearward upper walls 30 and 32 of the eductor tend to deflect settling matter and prevent it from unduly depositing and building up thereon. This is of importance in sewage disposal, where the settling solids are highly putrefactive with attendant disagreeable odors.

The eductor above described is especially adapted for the removal of activated sludge and other light sediments in large volume. Where lower volumes and/or heavier sludges are to be dealt with the modified form shown in Figs. 9, 10 and 11 may be advantageously employed. In this case the general construction of the tube may be the same as described above except that fewer sediment admission ports 34 are provided; and the tube has attached to it a plurality of V-shaped plows or

scraper blades 40 which deflect the sediment horizontally on the tank floor into the paths of such ports as the eductor is moved over the floor. In these figures the eductor is arranged for clockwise rotation whereas in Figs. 1-7 the eductor moves counterclockwise.

While a quadrilateral form of eductor tube has been specifically described above, other non-circular cross sections may be employed, such for example as the triangular forms 24^a and 24^b shown in Figs. 12 and 13 respectively.

What is claimed is:

1. A sediment eduction tube for substantially horizontal disposition adjacent and unidirectional movement over the floor of a sedimentation chamber, said tube being of a quadrilateral cross section providing a pair of downwardly divergent sediment deflecting upper walls, and an inclined forward wall which is provided with sediment admission ports adjacent its lower edge and with a longitudinal flange projecting forwardly below said

20 ports.

2. A sediment eduction tube for substantially horizontal disposition adjacent and unidirectional movement over the floor of a sedimentation chamber, said tube having a substantially uniform longitudinal taper and being 25 of a rectangular cross section providing a pair of downwardly divergent sediment-deflecting upper walls, and a pair of downwardly convergent lower walls one of which is ported along its lower edge for the passage of sediment therethrough and the other of which is extended 30 beyond such ported wall to provide a longitudinal flange therebelow.

3. An eduction tube for sedimentation chambers, comprising an elongated channel member of uniform width, the legs of which taper in depth substantially uniformly 35 from end to end and one of which is wider than the other; and a wall member having a series of longitudinally spaced ports, disposed between and secured to said channel legs in substantially the plane of the edge of the narrower leg, whereby a portion of the wider leg projects 40 beyond said wall member to provide a longitudinal flange adjacent the ports of the latter, the areas of said ports progressively increasing as the cross sectional area of the tube decreases.
